UNITED STATES PATENT OFFICE.

MARY J. SPENCER, OF BROOKLYN, NEW YORK.

SCHOLAR'S COMPANION.

SPECIFICATION forming part of Letters Patent No. 355,417, dated January 4, 1857.

Application filed June 18, 1886. Serial No. 205,526. (No model.)

To all whom it may concern:

Be it known that I, MARY J. SPENCER, of Brooklyn, New York, have invented certain Improvements in Scholars' Companions, of 5 which the following is a specification.

The objects of this invention are the simplifying of the construction and mode of operation of receptacles for school-children's implements, resembling that shown and described 10 in Letters Patent of the United States, No. 291,415, issued to me January 1, 1884, in respect of the particulars that they contain a water-proof pocket for holding the sponge and an elongated pocket for the reception of pencils and pens, and are composed of cloth or 15 other flexible material.

To this end the invention consists in making the scholar's companion, or receptacle for school-children's implements, in the form of 20 an oblong bag closed at both ends, but having in one of its sides a longitudinal slit, which serves as the mouth or opening through which access is had to the interior of the bag for the deposit of a sponge in one of its ends, which 25 is lined with water-proof material, and for the introduction of pencils and pens into its other end, which is suitably elongated to contain them. The central portion of the bag is encircled by two sliding gathering-rings, for 30 gathering into folds the fabric which they enclose, and, when desired, closing either or both the entrances to the sponge or pencil pockets, respectively. The central portion of the bag between the two pockets serves as the handle by which the receptacle is conveniently 35 grasped in the hand of the carrier.

The accompanying drawings of a scholar's companion containing the invention are as follows: Figure 1 is an elevation showing the 40 pockets closed by the gathering-rings, respectively. Fig. 2 is an elevation showing the water-proof sponge-pocket open and the pencil-

pocket closed. Fig. 3 is an elevation showing the sponge-pocket closed and the pencil and pen pocket open.

The scholar's companion shown in the drawings is made of cloth in the form of an oblong bag, A, closed at its ends and provided with a longitudinal slit, B, in one of its sides, through which access is had to its interior. 50 Two sliding gathering-rings, C C, which are drawn on over the ends of the bag, gather into folds the fabric composing the central portion of the bag, and either or both rings, when pushed to the ends of the slit B, serve, as the 55 case may be, to close either or both the pockets D and E in the ends of the bag A.

The pocket E is for holding a wet or moist sponge, and is lined with oiled silk, rubber cloth, or other water-proof material.

The pocket D is suitably elongated to adapt it for containing pencils and pens.

To remove the sponge from the pocket E, the rings C C are pushed to the end of the slit B farthest from the pocket E, when the sponge 65 can be taken out. Similarly, to open the pocket D, the rings C C are pushed to the end of the slit B which is farthest from the pocket D.

I claim as my invention—

As an improved article of manufacture, the 70 hereinafter described receptacle for school-children's implements, the same consisting of an oblong bag, A, composed of flexible material, having a slit, B, in one of its sides, a suitably-elongated pencil-pocket D, at one end and a 75 water-proof sponge-pocket, E, at its other end, and having its central portion inclosed by the sliding gathering-rings C C, as and for the purposes set forth.

MARY J. SPENCER.
